UNITED STATES PATENT OFFICE.

JOHN P. CURRY, OF NEW YORK, N. Y.

TOOL FOR TWISTING WIRE TIES.

No. 908,649.

Specification of Letters Patent.

Patented Jan. 5, 1909.

Application filed May 4, 1908. Serial No. 430,750.

To all whom it may concern:

Be it known that I, JOHN P. CURRY, a citizen of the United States, residing at 62 West Eighty-ninth street, New York, county of New York, and State of New York, have invented certain new and useful Improvements in Tools for Twisting Wire Ties, fully described and represented in the following specification and the accompanying drawings, forming a part of the same.

The object of this invention is to furnish a means for securing upon the neck of a bag or other article a wire-tie having eyes or loops at its opposite ends. When such a wire is wrapped around the neck of a bag or other article, the portions of the wire adjacent to the end eyes may be twisted together leaving the eyes spread apart in such position that they may be readily used in untwisting the tie to open the bag. Such a wire-tie is valueless without such a tool as I have invented to twist the ends of the wire and leave the eyes suitably separated to use for untwisting. The application of such a wire-tie to a bag by hand is too tedious an operation to be of any practical value.

The invention consists of a tool which grasps simultaneously the eyes upon the ends of the wire-tie and by the mere pulling of the tool-handle serves to twist the wire ends together adjacent to the eyes, and can then be instantaneously detached from the wire eyes, leaving them in the desired position to be untwisted.

The tool is of the class having a spiral spindle with a handle fitted to the same so that the sliding of the handle causes the spindle to revolve. These elements are old; but in the present case I have added a swivel knob at one end of the spindle and a pair of hooks at the opposite end projected laterally upon the same, or opposite sides, from a head at one end of the spindle and disposed at a suitable distance apart to engage the eyes upon the wire-tie and to leave them when twisted in a suitable position for untwisting.

In the drawing, Figure 1 is a side elevation of the complete tool looking toward the ends of the hooks upon the head of the spindle and showing the handle and the knob in section; Fig. 2 shows the head of the spindle viewed from the side of the hooks; Fig. 3 shows the tie looped, as around the neck of a bag, and the eyes at the ends engaged with the hooks upon the tool; Fig. 4 shows a sec-

tion of the swivel knob; Fig. 5 shows the wire-tie with eyes at its opposite ends; Fig. 6 shows the wire-tie twisted (as upon the bag neck) with the eyes spread apart; and Fig. 7 shows the application of the tie and the tool to the neck of the bag.

The tool is formed with a spindle having a cylindrical body *a* and a spiral body *b* with handle *c* fitted at one end to the cylindrical body and at the opposite end to the spiral body so as to twist the spindle when slid over the spiral body. A head *d* is shown upon the end of the body *a* with two hooks *e* and *f* projected at equal distances from the center line of the spindle upon the same side of the head and at a suitable distance apart to engage the eyes *g* upon the ends of the wire-tie *h*, as shown in Fig. 3, and to leave the same in readiness for untwisting when they are twisted, as shown in Fig. 6. At the bases of the hooks the head is hollowed out beyond the axial line of the spindle, and the hooks are therefore projected across such axial line and are then recurved, as shown in Fig. 2, to form a secure engagement with the eyes upon the wire-tie. This construction for the hooks gives each of them upon the inner side a hollow or recess upon the center line of the spindle so that the wire when twisted is axially in line with the axis of the spindle. This produces a very smooth movement in twisting the wires and avoids any needless resistance. The spindle is provided with a swiveled knob *i* fitted to turn upon the end opposite the head *d*, to pull the spindle longitudinally through the handle *c* until the head is close to the handle, as shown in Fig. 7.

In using the tool, one of the eyes *g* upon the wire-tie is engaged with the hook *e*; the wire-tie is then looped around the neck *j* of the bag *k*, crossed over the portion on the hook *e*, and the other eye engaged with the hook *f*. This can be done with great facility by tipping the bag-neck a little sidewise as shown in Fig. 7, and the instant that the second eye is engaged with the second hook the handle *c* is pulled outwardly, and the spindle turns the head *d* with both the hooks, and twists the wire several times, as shown in Fig. 6. The crossing of the wire when applying the eyes to the hooks greatly reduces the force required in twisting the wire.

It will be noticed that the hooks are recurved toward the head *d* so that as the head rotates there is no tendency for the eyes *g*

to slip off of the hooks, especially as the wire is under tension owing to the pulling of the tool; but such recurved form permits the hooks to be instantly disengaged from the 5 eyes when the tie is twisted, by pushing the tool slightly toward the bag neck. The hooks leave the eyes separated as shown in Fig. 6, in the most favorable position for untwisting when it is desired to open the 10 bag.

When the wire has been twisted, the handle *c* is adjacent to the swivel knob *i*, and is restored to the opposite end of the spindle by holding the handle in one hand 15 and grasping the knob with the other and pulling the spindle through the handle. Without such knob, the handle could not be readily returned, as the spindle cannot be easily pushed through the handle, by reason 20 of the hooks upon the head, which turns when the spindle is pushed from that end.

The tool is designed with special reference to taking it apart for cleaning, when grit or dust penetrates to the working surfaces, as 25 the tool is especially designed and adapted for use in cement mills, flour mills, and analogous places, where it is greatly exposed to grit and dust. The cleaning of the tool is facilitated by the following construction: 30 The swivel-knob *i* is mounted upon a pin *l* integral with the spiral body *b* of the spindle, and is held detachably thereon by a screw *m*, as shown in Fig. 4, and the entire body of the spindle is removable from the 35 handle when the knob is detached, as the spiral body *b* can then be withdrawn from its nut and the interior of the handle readily wiped out, as well as the portions of the spindle. This construction is of great value 40 and importance, as it permits the continued use of the tool in places where it would be entirely disabled unless it could be readily cleansed. The construction of the hooks *e* and *f* is also peculiarly adapted to the twisting 45 of such wire-ties upon the neck of a bag or analogous situation, as the recurved points of the hooks retain the eyes of the wire-ties securely, when the handle is pulled to twist the wire, but permit the instantaneous disengagement of the hooks from the eyes when 50 the tool is pushed slightly in the opposite direction. It is preferable that the two recurved hooks should be substantially equidistant from the axis of the spindle, as shown 55 in Fig. 3, so that the tension upon the two ends of the wire tie may be equal and both

hooks may operate equally in forming the twist which locks the wires together adjacent to the eyes, as shown in Fig. 6.

I find in practice that it is preferable to 60 project the hooks *e* and *f* from the same side of the head *d*; but as the twisting movement of the spindle is always in the same direction, it is obvious that hooks may be projected from opposite sides of the head and 65 both projected forward in the direction of the movement, so as to retain the wire-eyes *g* upon the hooks while twisting, and permit their immediate disengagement by turning the spindle slightly to twist the hooks out of 70 the eyes.

Having thus set forth the nature of the invention what is claimed herein is:

1. The portable hand-tool for twisting wire ties having eyes upon their opposite 75 ends, consisting of the spindle *a* having the spiral body *b* with a handle *c* adapted to rotate the spiral body by a longitudinal movement, the end of the spindle having two recurved hooks *e* and *f* equi-distant from the 80 axis of the spindle and at a suitable distance apart to twist the ends of the wire tie and leave the eyes in position for untwisting.

2. The tool for twisting wire-ties, consisting of the spindle having the cylindrical 85 body *a* and the spiral body *b* with a handle *c* fitted to both bodies, and the head *d* upon one end of the spindle with two hooks *e* and *f* extended in the same direction laterally upon the head, equi-distant from the axis of 90 the spindle and at a suitable distance apart to hold the ends of a wire-tie in position for untwisting.

3. The tool for twisting wire-ties, consisting of the spindle having the cylindrical 95 body *a* and the spiral body *b* with a handle *c* fitted to both bodies, the head *d* upon the end of the cylindrical body *a* with two hooks *e* and *f* extended in the same direction laterally upon the head equi-distant from the axis 100 of the spindle at a suitable distance apart to hold the ends of a wire-tie in position for untwisting, and the knob *i* swiveled upon the end of the spiral body *b* for drawing the spindle lengthwise in the handle. 105

In testimony whereof I have hereunto set my hand in the presence of two subscribing witnesses.

JOHN P. CURRY.
